(57) CLAIM

The ornamental design for a brush head for electric toothbrush, as shown and described.

DESCRIPTION

FIG. 1 illustrates a perspective view of a brush head for an electric toothbrush, the stippling shading applied to some of the bristles show contrast in appearance.

FIG. 2 is a front view thereof.

FIG. 3 is a left side view thereof.

FIG. 4 is a right side view thereof.

FIG. 5 is a rear view thereof.

FIG. 6 is a top view thereof; and,

FIG. 7 is a bottom view thereof.

The broken lines in the drawings depict portions of the brush head for electric toothbrush which form no part of the claimed design.
